UNITED STATES PATENT OFFICE.

LOUIS ELI WEINMANN, OF NEW YORK, N. Y.

CONVERTIBLE BED AND DAVENPORT.

1,031,304.

Specification of Letters Patent.

Patented July 2, 1912.

Application filed August 5, 1909. Serial No. 511,319.

To all whom it may concern:

Be it known that I, LOUIS E. WEINMANN, a subject of the Emperor of Germany, and a resident of the city of New York, borough 5 of Manhattan, in the county and State of New York, have invented a new and Improved Convertible Bed and Davenport, of which the following is a full, clear, and exact description.

10 The invention relates to the known article of furniture that normally has the general form of a davenport, but which may be converted into a bed.

It is my object to provide a new article of 15 this general character greatly improved in various particulars as regards both the mechanical features and the esthetic appearance of the structure. Important desiderata in articles of the character referred to are 20 the possibility of converting the structure from davenport to bed form, and vice versa, with a minimum expenditure of physical energy; effecting the conversion conveniently without bodily moving the whole 25 structure from its normal position near the wall of the room, and the prevention of any damaging contact with the wall; these I obtain very effectively with my improved 30 structure.

35 A distinguishing feature of my invention is that my improved article of furniture when adjusted as a davenport, presents the conventional appearance of an ordinary davenport; the bed features are well disguised; the operative devices and mechanism employed are normally concealed, and the convertible character of the structure is 40 not apparent.

In the preferred form of my invention the 45 three main elements of the seat, back and mattress, with their individual appurte- nances, are mounted to be moved bodily in- ward and outward on a relatively fixed base, and are then shifted relatively to one an- 50 other to so dispose the parts as to constitute a bed. In converting the structure into a bed, after the whole superstructure is moved outward on the base, the back is lowered and then occupies the position on the base that 55 the seat occupies when the parts are ar- ranged as a davenport, the movement of the back from an approximately vertical to a horizontal position serving to move also a 60 mattress section.

The individual elements of the seat, back 55 and mattress of my improved article embody distinctive features, alone and in their novel correlation, which will best be pointed out in detail in explaining the structural em- bodiment elected by me for the illustrated 60 example of the invention. It is desirable to here mention, however, that my improved seat comprises a mattress that folds together in two folds onto the seat frame, the upper layer or fold when the structure is adjusted 65 as a davenport, forming the seat cushion; this upper fold of the mattress presents on said upper surface an upholstered cushion; its opposite side constitutes one section of a mattress surface; the line of folding of the 70 mattress is at the inside; that is, at the angle formed by the seat and back, the opening between the mattress folds or layers be- 75 ing at the outer edge of the seat. Moreover, the combined seat cushion and mattress 80 fold includes an interior frame which serves to give permanent form and firmness to the seat cushion as effectively as does the fixed seat frame of the ordinary davenport. In 85 form this cushion frame is such that the ele- ment of comfort afforded by the seat is fully maintained, and the parts of the cushion frame are so disposed that no unyielding surface or rigid member is presented at the 90 front angle of the seat surface to cause dis- comfort. The cushion frame, furthermore, constitutes a carrier for the top fold form- 95 ing the seat cushion and mattress section, and I may advantageously, as in the pre- 100 ferred form, establish a mutually coöpera- tive lever-connection between the movable davenport back and the cushion frame; thus the lifting of the mattress frame enables the back to gravitationally assume the horizontal position, and this downward move- 105 ment of the back gives continued movement to the mattress.

The preferred mode of mounting the superstructure movably on the base is through the medium of a sliding carrier 100 means to which the back, the seat, and the mattress are secured, together with their operative appurtenances. The seat and the mattress are mounted to be raised, if desired, to afford access to the box-like base without 105 disturbing the back.

A further special feature of my invention is an auxiliary supporting device for pre-

venting the lowering of the back until it and the seat have been moved bodily outward, thereby preventing damaging contact of the back with the adjacent wall of a room.

5 Novel leg attachments for supporting the seat frame in its outer position as a bed section are also provided, and a novel controlling means for said legs.

Other distinguishing features will appear 10 in connection with the specific description hereinafter to be given.

Reference is to be had to the accompanying drawings forming a part of this specification, in which similar characters of reference indicate corresponding parts in all 15 the views.

Figure 1 is a general perspective view of the frames of which my davenport and bed are composed, with the mattresses and cushions removed to expose the operative mechanism: Fig. 2 is a side view partially broken away, showing the parts in a davenport position; Fig. 3 is a side view showing the davenport converted into a bed; Fig. 4 is a cross 20 section showing the frames with cushions and mattresses removed for clearness of illustration, with the suitable seat frame and parts carried thereby withdrawn, in the first step of converting the davenport into a bed; Fig. 5 is a cross section of the frames with 25 cushions and mattresses removed, showing the davenport converted into a bed; Fig. 6 is a top plan view which shows a detail of construction, the view representing a roller carried upon the stationary under frame and serving to reduce the friction of a certain 30 sliding member to be hereinafter more fully described; Fig. 7 is a side view of the same roller; Fig. 8 is a side view of the end of a 35 channel iron carried upon the sliding member, the view showing two friction rollers; Fig. 9 is a section on the line $x-x$ of Fig. 4; Fig. 10 is a section on the line $y-y$ of Fig. 4; Fig. 11 is a cross section of a slight modification showing an automatically-swinging 40 support for holding the seat when access is desired to the under frame, certain friction rollers for the seat section being omitted from this view; Fig. 12 is a similar view 45 of the form illustrated in Fig. 11, showing the parts in another position; and Fig. 13 is a detail of a rocking arm which serves to support the davenport back in certain 50 positions.

55 My improved convertible davenport and bed comprises in general, in the form illustrated, a stationary base frame or box-frame A, having mounted thereon for bodily movement in unison a seat-frame B, a swinging 55 mattress frame C, and a swinging davenport back D. In converting the davenport into a bed, the mattress-frame C, and with it the back and the seat-frame are slid outward on the base frame A by pulling frontward the 60 mattress frame C, then the mattress-frame C

is lifted and the davenport back lowers into a horizontal position and the mattress-frame is carried over onto the new horizontal back D.

It will be observed that in its outer and lowered position, the back D occupies the 70 position on the base A that is occupied by seat frame A when the structure is arranged as a davenport.

The under frame or box-frame A comprises suitable side members 1, front and back members 2^a and 2^b, and a bottom 75 3. If so desired, the box-frame A may be employed for the storing of bedding.

The seat frame B is shown as comprising 80 a bottom front member 12^b and a bottom rear member 12, a front board 12^a attached to the bottom member 12^b, and sides 10 connecting the bottom rear member 12 and the front bottom member 12^b and front board 12^a. In 85 connection with the back, mattress frame and seat frame, a sliding carriage may advantageously be employed preferably in the form of channel irons 9, from which the said back, mattress frame and seat frame receive 90 support through suitable connections hereinafter described. The tops of the sides 10 may be higher than the top of the front board 12^a, as clearly shown in Fig. 4.

The davenport back D comprises upper 95 and lower members 15 and 15^a and side members 16 and 16^a, connecting the members 15 and 15^a. The sliding seat frame B may contain springs 17 (Fig. 2), which may be box springs or any other springs suitable for the 100 purpose of supporting an overlying mattress resiliently. I prefer to use a double mattress 18, the parts being folded upon each other when the bed is converted into a davenport, as shown in Fig. 2, and spread apart 105 to form an open bed surface, as shown in Fig. 3. The line of folding of the mattress, it will be observed, is at the back, at the angle of the seat and back, the mattress thus opening at the outer edge of the seat. The 110 upper section of the foldable mattress 18 is suitably fastened to the normally under side of the swinging mattress frame C, by attachment to the side members 19 of the said frame. The upper surface of the top mattress fold carried by frame C is in the form of a seat cushion 50. The davenport back 115 D is provided with a pad 21 which is secured to the frame members 15, 15^a, 16, 16^a in any suitable manner, and made resilient by means of springs (not shown) in any approved manner.

A carrier means for the superstructure is shown in the form of slides composed each of channel irons 9 on which the seat frame, 125 back and mattress are mounted in a manner hereinafter described. The channel irons 9 are supported and guided in the following manner: Each of the side members 1 of the base or under frame A is provided at its 130

top with a groove 4. A system of friction rollers, separately shown in Figs. 6, 7, 8, 9 and 10 are provided. There are two sets of these rollers, consisting each of two pairs, 5 two pairs being attached to the under frame A, the other two pairs to the slides 9. Each pair of rollers comprises one roller rotating horizontally and another roller rotating vertically. The two pairs of rollers 5 and 5^a 10 of the under frame are mounted, each pair on an angle plate 7 which is fastened to the side member 1 of frame A, by means of screws 8 (Fig. 6). The roller 5 turns on a horizontal axis and is journaled in the vertical member 7^a of the angle plate 7. The roller 5^a turns on a vertical spindle secured to the horizontal member of the plate 7. The two pairs of rollers 5 and 5^a are received in the channel irons 9. The inner end of 15 each channel iron 9, as shown in Fig. 8, carries a pair of rollers 13 and 14, the roller 13 turning on a horizontal axis, and the roller 14 on a vertical axis, both being received in a groove 4 of the under frame A. The 20 rollers 13 and 14 may be conveniently carried upon a plate 15 riveted to the channel iron. As a result of this double system of rollers, it is evident that the slides 9 carrying the superstructure can be drawn 25 forward upon the under frame A or pushed back with ease. As the slides 9 travel forward the rollers 13 and 14 travel with them in the groove 4, the roller 13 absorbing the vertical friction and the roller 14 the horizontal friction. Similarly, the rollers 5 and 30 35 5^a secured to the stationary under frame absorb the vertical and horizontal friction of the slides as they travel back and forth.

To the inner end of each channel iron 9 a 40 post 20 is fastened, as shown in Figs. 4, 5 and 10. Upon the post 20 the seat frame B, the mattress frame C and the davenport back D all swing. To the inner face of each side member 10 of the frame B, a metal 45 strap 21^a is fastened near the top, the inner end of the strap 21^a being pivotally connected with the post 20 as at 22. The frame B has a limited swinging movement around this pivot 22 in order that access may be 50 had to the stationary under frame or box-frame A to remove the bedding therein contained, as shown in Fig. 12. The upper end of the post 20 is offset rearwardly. To the offset 20^a of each post 20 a lever 23 is fulcrumed to the side members 19 of the mattress frame C, as at 24. The lever 23 is articulated for a purpose that presently will appear, the end 26 being pivoted at 27 and the downward movement of the end 26 being 55 limited by a stop pin 25. To the side members 16, 16^a of the davenport back frame D metal straps 28 are secured; each metal strap 28 is provided with a roller 29 adapted to rest against the end 26 of lever 23 and to 60 65 swing said lever 23 on its fulcrum and thus

raise frame C when the back D is thrown down into horizontal position. The lower end of each strap 28 is bent to form a curved arm 29^a which is connected with the post 20 by a pivotal connection 30. One end of a 70 bent link 31 is connected with each lever 23 by a pivot 32, and at the other end with a leg 33 by means of a pivot 34. Each leg 33 is formed with a short angularly-disposed member 33^a which swings on a block 33^b 75 attached to the side member 10 of the seat frame B, around the pivot 35.

In converting the davenport into a bed, the mattress frame C is drawn forward by hand, thereby carrying with it the davenport back D and the seat frame B. Simultaneously with this forward movement the mattress frame C is lifted, so that the back drops into horizontal position by its own weight into the position previously occupied 80 by the seat frame B, the mattress frame C at the same time dropping on the lowered back. In this position of the parts, it will be observed that the seat cushion 50 is completely reversed in position and lies on the 85 back cushion 21, and that the two sections of the mattress 18 are spread apart and lie in the same horizontal plane, thereby presenting a bed surface. As the davenport back thus swings downward and backward, 90 the rollers 29 on straps 28 of back D press downward on the end 26 of the lever 23. Hence, as the back D swings downward and backward, the mattress frame C is simultaneously caused to swing upward to the 95 position shown in dotted lines in Fig. 5. The mattress frame C is thus elevated without undue muscular effort upon the operator's part, inasmuch as the davenport back and the mattress frame C are in effect counterbalanced during the entire downward movement of the davenport back, because it will be observed that the weight of back D is on the shorter arm of lever 23, while the weight of the mattress frame C and the 100 mattress fold carried thereby act on the longer arm of said lever. When the mattress frame C reaches the position which is shown in Fig. 5 in dotted lines, the force of momentum usually carries it over the vertical line so that it falls onto the davenport back D, and the mattress 18 is spread open in the position shown in Fig. 3. As the davenport back swings downward, the bent link 31 is thrust forward and rocked on the 105 pivot 32; as it does so, the leg is caused to rotate upon the pivot 35 so that the legs are thrown outward and downward until they 110 assume the supporting position shown in Fig. 5.

In converting the bed into a davenport, in other words, to throw the parts from the position shown in Figs. 3 and 5 to the position shown in Fig. 2, the series of operations is reversed. The mattress frame C is first 115 120 125 130

lifted to the position shown in dotted lines in Fig. 5, an operation which is comparatively easy because of the light weight of the said mattress frame C. When the mattress frame C is in the position shown in dotted lines in Fig. 5, the ends 26 of levers 23 are brought against the rollers 29. By now swinging the mattress frame C forward and downward the back D is simultaneously raised, the leverage and weight of the mattress frame C assisting in this elevation of the davenport back D, by counterbalancing same. As the davenport back D rises into the position shown in Figs. 2 and 4, the link 31 is drawn backward, thereby causing the leg 33 to be drawn up into the position shown in Fig. 4.

When the seat frame B is lifted upward to give access to the box A underneath, it is desirable that some means be provided to support the back D in the position shown in Fig. 4, because it will be observed that the mentioned articulation between the body of lever 23 and its end 26, causes the lever to flex at its joint, as in Fig. 12, thereby withdrawing from the seat back the support afforded by the rollers 29 bearing on the unyielding lever arm 26. Accordingly I employ an extensible support which consists of two pairs of links 36 and 37, each pair connected by a pivot 38, the link 36 of each pair being connected with the under frame or box frame A by a pivot 39 on the outer end of a metal strap 40 secured to the back board 2^b of the under frame. Each link 37 is in turn connected with the member 15^a of the davenport back frame by means of a pivot 41. A transverse rod 16^b, connecting the sides 16^a and 16 of the davenport back frame, is adapted to press outward against the links 37, and upon the return movement, to be pressed against by said links. When the parts are in the position shown in Figs. 1 and 12, the bar 16^b rests against the links 37, and then supports the back in an approximately upright position, and from said figures it will be understood that with the back D in its rearward, approximately upright position, said back if tending to swing downward, must bear through rod 16^b on the folded extensible support 36, 37, so that said back cannot move downward until it is first moved outward on the fixed base. Thus the back cannot fall backward to contact with the wall. It is evident that as the seat back D slides forward upon the base frame A, the links 36 and 37 will spread apart and permit the back to lower, for as the back D is swung down to assume the position shown in Fig. 5, the links 36 and 37 will spread still apart, swinging as they do so around their pivots 39 and 41. In converting the bed into a davenport, the links 36 and 37 assume the position shown in Fig. 4, after the davenport back D has reached its raised

position. As the seat frame D is slid back on the under frame, the links 36 and 37 close up as shown in Figs. 1 and 12.

By referring to Figs. 1, 4 and 5, it will be observed that to the outer end of each side member 19 of the mattress section C an angle iron 42 is fastened, the angle irons 42 being connected by the board 11. It will be observed from Fig. 1 that the top of the board 11 lies below the side members 19 of the mattress frame C. The free space left between the two side members 19 and the board 11, is filled by a downward extension 50^a on the front of the seat cushion 50, as appears clearly in Fig. 2. As a result of this construction there is no rigid or unyielding member at the top outer angle of the seat cushion.

In order to support the seat frame and mattress section in the raised position shown in Fig. 12, I may employ any form of brace suitable for the purpose. In Fig. 12, I have shown a preferred form of such brace. This preferred form of brace comprises a long member or leg 43, and a short, doubly bent member 44, the brace being pivoted at 45 to a block secured to the front board 12^a of the seat frame B. A link 46 is loosely attached to the end of the short member 44, and a handle 47 is loosely secured to the outer end of the link 46. A slot 48 is cut into the front board 12^a of the sliding seat frame B to permit the passage of the chain or link 46, and a space is left between the seat frame and the front extension 50^a of the mattress frame. When the parts are in their normal position, a pin 49, protruding from the front member 12^a of the seat frame (Fig. 1), passes through a hole 50 in the link 46 to retain the handle. A recessed block 49^a, is fastened to the inner surface of the front board 2^a of the under frame or box frame A, which block serves as a rest for the member 43 of the brace. When it is desired to lift the seat frame B and the mattress frame C in order to gain access to the under frame or box frame A, the handle 47 is pulled a little down and upward to detach the link 46 from the pin 49. By means of the handle 47, the seat frame B and the mattress frame C are then swung up into the position shown in Fig. 12, and the long member 43 of the brace is simultaneously swung outward and made to rest on the block 49^a. When it is desired to restore the mattress frame C and the seat frame B to the position shown in Fig. 11, the operator lifts the seat frame B slightly by means of its front member 12^a, so that the long arm 43 is lifted from the block 49^a. The seat frame B and the mattress frame are then lowered, and simultaneously the long member 43 of the brace is swung upward by pulling on the handle 47 and link 46; and is then secured by engagement of the link 46 with the pin 49.

In Figs. 5 and 11 I have shown a pillow support. This support consists of the member 61 hinged at 60 to the mattress frame C, the member 62 hinged at 64 to the link 5 65 which is hinged at 68 to the seat frame B, and the member 63 carried by the hinged end of the mattress frame, the parts 61, 62 and 63 being pivotally connected as shown at 63^a, 66 and 67. This support is 10 not claimed in the present application.

Having thus described my invention, I claim as new and desire to secure by Letters Patent,—

1. In a convertible davenport and bed, a 15 base and a structure slidable on said base, said structure comprising a swinging back, a seat frame, a swinging frame movable to overlie the seat frame or the back when lowered, a mattress folding onto the seat frame, 20 one fold of the mattress being secured to said swinging frame, and means associated with the swinging frame and back so that the sliding of the structure will cause the back to swing down on the base and the 25 swinging frame to swing down on the back.
2. In a combined davenport and bed, the combination of a base, a seat frame slidable on the base, a back pivoted to the seat frame, a mattress frame also pivoted to the seat 30 frame, and a connection between the back and mattress frame, whereby when the seat frame is slid outwardly on the base, the back can be swung down on the base and the mattress frame swing down on the back.

- 35 3. In a combined davenport and bed, a base and a structure slidable on the base, said structure comprising a seat section, a back section swinging from an approximately upright position to a position in 40 line with the seat section to rest upon the base, a mattress frame having a supporting and guiding connection with the back section, whereby it may be moved to rest upon either the back section when lowered or 45 upon the seat section, and a two-part mattress normally folded on the seat section and having one fold attached to the mattress frame.

- 50 4. A combined davenport and bed, comprising a base, a seat section slidable on the base, a back section movable in line with the seat, a mattress foldable on the seat, the upper fold of the mattress constituting a seat cushion and being movable over the 55 lowered back to bring the normally opposite surfaces of the mattresses in line with each other, and a swinging frame on which the said upper fold of the mattress is secured.

- 60 5. A combined davenport and bed, comprising a seat section, a back section movable in position in line with the seat, a swinging mattress section, and a counterbalancing connection between the said swinging mattress section and the back, said 65 connection acting to maintain the counter-

balancing effect during the movement of the back from one position to the other, the mattress section being independently movable for a portion of its travel from one position to the other.

6. A combined davenport and bed, comprising a seat section, a back movable to a position in line with the seat section, a mattress frame movable both independently and in unison with the back, and means for supporting the back in an approximately upright position while the seat section and mattress frame are bodily raised or lowered independently of the back section. 70

7. A combined davenport and bed, comprising a seat, a back pivoted to the seat movable in line with the said seat, and a mattress frame pivoted to the seat, and means connecting the mattress frame with the back, whereby the mattress frame is 80 movable in unison with the back and also independently when the back is in either of its terminal positions. 85

8. A combined davenport and bed, comprising a seat, a back section adapted to 90 swing through an arc of about 85° to align with the seat section in a horizontal position, and a mattress frame movable through an arc of approximately 180° and movable with the back section during the travel of 95 said back section and also movable independently of the back section through an arc of about 90°.

9. A combined davenport and bed, comprising a base, a seat section slidable on the 100 base, a leg swinging from a fixed center on the seat section, a back section movable to a position in line with the seat section to rest on the base and form with the seat when slid outwardly a bed, and connections between 105 the leg and the back to move the leg into and out of operative position by the movement of the back.

10. A combined davenport and bed, comprising a base, a seat section slidable on the 110 base, a back section movable to a position in line with the seat section to form a bed, a mattress section having a counterbalanced connection with the back section, the mattress section and the seat section being together vertically movable independently of the back section, and means for holding the mattress section and the seat section in an elevated position. 115

11. The combination of a base, a swinging 120 seat section superimposed upon the base, a gravitating brace pivoted upon the swinging seat section and adapted to engage the base to hold said seat section in its uppermost position, and a handle attached to the 125 brace.

12. The combination with a base, a swinging seat section superimposed upon the base, a brace pivoted on the swinging seat section, and a handle operatively connected with the 130

- brace and serving as means for simultaneously lifting the seat section and swinging the brace into a position to support the seat section when said section is in elevated position.
13. In a convertible bed and davenport, the combination of a seat section, a mattress section and frame movable to a position in alinement with the seat section, and a mattress foldable on the seat section, one of the mattress folds being carried by the mattress frame and the other resting on the seat section, the mattress frame having a depending angular extension.
14. In a convertible davenport and bed, the combination of a base, a frame slidably mounted on the base, a seat frame pivoted to and carried by the sliding frame, a swinging back, a swinging mattress frame, and pivoted connections between the back and mattress frame with the sliding frame, whereby the back can be swung upon the base and the mattress frame upon the back.
15. In a convertible davenport and bed, the combination of a base, a pivoted and sliding seat frame mounted on the base, a swinging back, a swinging mattress frame, and connections between the back and mattress frame whereby the back will be swung upon the base and the mattress frame upon the back when the seat frame is slid outwardly.
16. In a convertible davenport and bed, the combination of a base, a pivoted and slideable seat frame on the base, a swinging back, a swinging mattress frame, connections between the back and mattress frame to permit the back to swing down onto the base and the mattress frame on the back when the seat frame is slid outwardly, and a support for the back when the seat frame is swung on its pivot.
17. In a convertible davenport and bed, the combination of a seat frame, a back pivoted to the seat frame, a mattress frame, a jointed lever carried by the mattress frame and pivoted to the seat frame, and a member on the back with which one member of the jointed lever engages.
18. In a convertible davenport and bed, the combination of a seat frame carrying posts whose upper ends are offset, a back pivoted to the said posts, a mattress frame, a jointed lever carried by the mattress frame and pivoted to the offset end of the post, and rollers on the back and with which one member of the jointed lever engages.
- In testimony whereof I have signed my name to this specification in the presence of two subscribing witnesses.
